United States Patent Office

Des. 233,797

Patented Nov. 26, 1974

233,797

PIANO

Dennis J. Barket, Greenwood, Miss., assignor to
D. H. Baldwin Company, Cincinnati, Ohio

Filed Nov. 24, 1972, Ser. No. 309,461

Term of patent 14 years

Int. Cl. D17—01

U.S. Cl. D56—9

FIG. 1

FIG. 1 is a front, top and left side perspective view of a piano showing my new design.

FIG. 2 is a front elevational view.

FIG. 3 is a right side elevational view.

The back of the piano (not shown) is conventional.

I claim:

The ornamental design for a piano, as shown and described.
